US0D1063179S

(12) **United States Design Patent** (10) Patent No.: **US D1,063,179 S**
(45) Date of Patent: ** Feb. 18, 2025

(54) **PORTABLE LAMP**

(71) Applicant: **Shenzhen Intellirocks Tech. Co., Ltd.**,
Shenzhen (CN)

(72) Inventors: **Wenju Zhou**, Guangdong (CN);
Wenlong Wu, Guangdong (CN)

(**) Term: **15 Years**

(21) Appl. No.: **35/520,182**

(22) Filed: **Jan. 6, 2024**

(80) **Hague Agreement Data**

Int. Filing Date: **Jan. 6, 2024**

Int. Reg. No.: **DM/235291**

Int. Reg. Date: **Jan. 6, 2024**

Int. Reg. Pub. Date: **Mar. 1, 2024**

(30) **Foreign Application Priority Data**

(57)

CLAIM

The ornamental design for a portable lamp as shown and described.

DESCRIPTION

1. Portable lamp

1.1 : Perspective

1.2 : Perspective

1.3 : Front

1.4 : Back

1.5 : Left

1.6 : Right

1.7 : Top

1.8 : Bottom

The broken lines shown in the drawings are included for the purpose of illustrating portions of the portable lamp that form no part of the claimed design.

1 Claim, 8 Drawing Sheets
